UNITED STATES PATENT OFFICE

BYRON C. BOOTH, OF MUSKEGON HEIGHTS, MICHIGAN, ASSIGNOR TO THE BRUNSWICK-BALKE-COLLENDER COMPANY, OF CHICAGO, ILLINOIS, A CORPORATION OF DELAWARE

TOILET SEAT

Application filed November 11, 1927, Serial No. 232,627. Renewed September 12, 1930.

My invention relates to toilet seats, and more particularly to hinges therefor.

An object of my invention is to provide a toilet seat having a hinge which is concealed from view when the seat is in lowered position and which therefore has an especially attractive appearance.

Another object of the invention is to provide a seat and hinge of this type with concealed devices for checking the movement of the seat so that it may be held in an elevated and rearwardly inclined position.

Other objects and advantages will appear as the description proceeds.

15 Referring to the drawings:

Fig. 1 is a top plan view of a seat embodying my invention;

Fig. 2 is an enlarged horizontal sectional view of the rear of such a seat, and

20 Fig. 3 is a sectional view taken on line 3—3 of Fig. 2, showing the seat attached to a closet bowl, which is shown in dotted lines, the seat being shown in raised position in dotted lines.

25 My preferred embodiment comprises a core 1, preferably made of laminated wood. In the rear of the core is an insert made of cast iron or similar material. A portion of the insert is embedded in the core, this portion 30 being in the form of a flat plate 3, preferably roughened or corrugated as shown to increase its area of contact and consequent gripping power. Adjacent the plate 3 is a shoulder 4 which abuts snugly against the

35 rear of the core.

Rearwardly extending from the shoulder is a shell having a top 5 and sides 6 in which are formed aligned apertures 7. The top portion is curved downwardly in back to 40 form a rear portion 8.

A coating 9 of rubber, a phenolic condensation product, or a similar plastic material extends continuously over the entire core and insert.

45 Standards 10 having threaded posts 11 are secured to a closet bowl 12 and extend upwardly and rearwardly therefrom, into the cavity defined by the shell and have pintles 14 thereon which extend into the apertures 50 7 in the insert.

The seat may be moved to a position slightly beyond the vertical, at which point the curved rear portion 8 of the shell will abut against the standards, thus checking the rotation of the seat.

55

In constructing the preferred embodiment of the invention, the core is built up of laminated wood and shaped to the form of a toilet seat. An opening is cut in the rear and the plate 3 of the insert driven therein. A coating of rubber or other plastic material is then molded over the core and the projecting shell-like portion of the insert, and, in the case of rubber, vulcanized thereon.

60

It will readily be seen that a seat embodying my invention will be unusually attractive in appearance because of the fact that a perfectly smooth surface is exposed when the seat is lowered, with no hinge elements in view. Such a structure is also obviously 70 highly sanitary.

65

My invention may take various modified forms. For example, the core may be made of ground cork, wood shavings, or of various kinds of fiber held together by a suitable 75 binder, or shoddy rubber, coated as above described. Or, the seat may be molded as a solid unit of plastic material.

70

Other modifications will come within the spirit of my invention as defined by the appended claims, and I do not wish to be limited to the embodiments described.

75

What I claim and desire to secure by Letters Patent is:

1. The combination of a toilet seat having 85 a cavity in the rear portion thereof closed on all sides except at the bottom of the seat, and a standard extending into said cavity and supporting said seat for pivotal movement.

90

2. The combination of a toilet seat having a cavity in the lower rear portion thereof, closed on all sides except at the bottom of the seat, and a standard extending into said cavity and supporting said seat for pivotal movement, and engageable with the rear wall of said cavity to limit the rotation of said seat.

95

3. The combination of a toilet seat body formed of a plastic composition and having 100

a cavity in the rear portion thereof closed on all sides except at the bottom of the body, and an upwardly and rearwardly extending standard concealed within said cavity when said body is in lowered position and pivotally supporting said body and engageable with the rear wall of said cavity to limit the rotation of said body.

4. The combination of a toilet seat comprising a core, a metallic insert in the rear of said core having a cavity in the lower rear portion thereof, a coating of plastic material completely covering said core and said insert, a standard concealed within said cavity when said seat is in lowered position, and a pintle on said standard extending into a wall of said cavity for supporting said seat for pivotal movement.

5. The combination of a toilet seat comprising a core, a metallic insert in the rear of said core having a cavity closed on all sides excepting at the bottom, a coating of plastic material completely covering said core and said insert, a standard concealed within said cavity when said seat is in lowered position, and a pintle on said standard extending into a wall of said cavity for supporting said seat for pivotal movement.

6. A toilet seat comprising a wooden core, a metallic insert in the rear of said core having a shell-like member projecting from said core, a pair of standards concealed within said member when said seat is in lowered position and pivotally supporting the same, and a thick coating of plastic substance covering said core and insert and presenting an uninterrupted surface at the points of juncture of said core and said member.

40 7. A toilet seat comprising a wooden core, a shell-like member secured to the rear thereof and projecting therefrom, a coating of hard rubber molded on said core and said member and presenting an uninterrupted surface at the points of juncture of said core and said member, and a standard concealed within said member when said seat is in lowered position and having a pintle projecting into an opening in the wall thereof for pivotally supporting said seat.

8. A toilet seat comprising a wooden core, a metallic insert in the rear of said core having a shell-like member projecting therefrom, a coating of hard rubber molded on said core and insert and presenting an uninterrupted surface at the points of juncture of said core and said member, and a standard concealed within said shell-like member when said seat is in lowered position and having a pintle projecting into an opening in the wall of said member for pivotally supporting said seat.

BYRON C. BOOTH.
